CLAIM

I claim the ornamental design for a decorative yard pond interlocking edging segment, as shown and described.

DESCRIPTION

FIG. 1 is a perspective view of a decorative yard pond interlocking edging segment showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, the bottom plan view being a mirror image thereof; and,

FIG. 7 is a perspective view of the decorative yard pond interlocking edging segment shown on a reduced scale in condition of use with a like segment thereof, the broken lines thereof and of environmental matter are for illustrative purposes only and form no part of the claimed design.
